UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,852, dated October 24, 1893.

Application filed September 19, 1893. Serial No. 485,917. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification.

The design consists of a series of wreaths formed of branches of leaves arranged at equal distances apart over the surface of the paper, the upper portion or top row of wreaths forming the border portion of the design being connected by festoons of narrow bell-shaped ornaments as represented by the accompanying drawing.

What I claim is—

1. The design for wall paper herein shown and described.
2. In the design for wall paper the border herein shown and described.
